BAG HOLDING AND DISPENSING RACK

Charles L. Greer, Knoxville, Tenn.

Application November 18, 1946, Serial No. 710,606

3 Claims. (Cl. 211—50)

1

This invention is a paper bag holding and dispensing rack expressly constructed and designed to conveniently harness and contain a batch or stack of standard-type grocery store commodity bags, the latter being held in a manner to permit same to be withdrawn one-by-one, with one hand, for ready use.

One object of the invention is to position and confine the batch or pack of bags with their lower or closed ends down in said rack and their upper or mouth ends sitting up, the usual notches or cut-outs in the front panels facing outwardly and toward the user, whereby to ready each successive bag for convenient grasping and withdrawal from the rack.

Another object of the invention is to provide a simple and practical rack which has means at its upper end for hooking over and releasably retaining the rear panels or sides of the bags in such a manner that the notch or cut-out in the front panels is accessibly free for insertion of a human finger, making it easy to grab a bag and pull it forwardly and outwardly, said means momentarily checking and retarding the rear panel and causing it to lag behind the front panel, this so that, as the bag is yanked from the rack, the mouth is opened. Thus, with the mouth so conditioned the bag is flipped in the air and air trapped therein to completely open said bag for quick filling in an obvious manner.

A further object is to combine with the mouth opening feature, additional friction check means which acts simultaneously as a brake against and in the infolded longitudinal edge folds to spread and partly expand said folds, this at the transverse center of each bag, and in such a manner as to further assist in the automatic opening step of said bags.

Another object of the invention has to do with an open work rack in which the bags are stacked in orderly fashion for ready access and removal, said rack embodying so-called automatic means for partially opening the bags, one phase of the means co-acting with the open mouth of the bag, and another aspect thereof co-acting with the infolded longitudinal edges, there being a projection in the rack which is adapted to poke into adjacent portions of the pack of bags to bend and flex the latter, to serve as a sort of fulcrum element and to put transverse portions of the bags under tension to provide the desired follow-up action and proper functioning of the bag opening devices.

A further object of the invention is to provide a bag holding rack in the form of an open-work frame, said frame being made up of two principal horizontal and vertical units, both units being of general U-shaped form, the vertical unit being extensible for adjustment purposes.

Other objects, features and advantages will

2

become more readily apparent from the following description and the accompanying illustrative drawings.

In the drawings, wherein like numerals are employed to designate like parts throughout the views:

Figure 1 is a front view showing the open-work, cruciform frame constituting the rack, and also showing, in dotted lines, the manner in which bags are held therein for expeditious grasping and removal.

Figure 2 is a side elevational view, this showing the bags in full lines and showing the upper half portions of the outermost bag released and partly withdrawn.

Figure 3 is an enlarged fragmentary, in section and elevation, view of the adjustable part of the main U-shaped unit.

Figure 4 is a cross-section on the plane of the line 4—4 of Figure 1, looking in the direction of the arrows.

Referring now to the frame or rack in terms of generalities, it will be seen that it is characterized by an adequate open-work frame structure for the reception of a stack or pack of bags, these being of the ordinary grocery store variety, the mouth ends of the bags being disposed upwardly and the reinforced bottom or base portions disposed in an opposite or downward direction. Automatic means is incorporated to partly open the bags. That is to say, means is at the top of the rack for engaging the mouth portions of the bags as they come out one-by-one, the means serving to exert a slight drag on the inner wall or panel of the bag as the outer wall is pulled, by hand, from the rack. This starts the mouth of the bag to open. Then, and progressively as the second step, the intermediate longitudinal edge portions, the portions which are folded in as usual, are acted upon by means incorporated in the rack, which means serve to function somewhat as a dragging brake which hooks into the fold as the fold is being pulled out, thus delaying the action sufficiently long to spread and partly expand both folds. It follows that as the bag is grasped and withdrawn with one hand, it is then ready to be yanked and swirled into the air in the customary fashion to permit same to be "blown" into inflated form. Means is provided at the bottom of the rack for supporting the bottom portions of the bags and means is provided on the upper central portion to put the bags under a requisite degree of tension.

The principal U-shaped unit, the one which is vertically disposed is of an extensible and retractile or adjustable character and embodies an L-shaped lower portion or section 6, this embodying a limb 7 which is adapted to be secured to a suitable support by screws or the like

8. There is a laterally and outwardly inclined limb 9 at the bottom which terminates in an up-bent keeper-hook 10 for the lower or base portions A of the paper bags B. A shorter L-shaped part 11 is provided as the upper portion of the frame and this includes a vertical limb 12 which is slotted at 13 and bolted as at 14 to said limb 7. There is an overhanging and outstanding limb 15 at the top which ends in a retaining and trip finger for the mouth portions of the bags, said finger comprising a depending lug 16 forming an appropriate detent and trip element. The limb 7 is provided with a fulcrum prong or equivalent means which is generally denoted by the numeral 17. This comprises a simple prong 18 which stands out as shown in Figure 2 and which has a laterally bent inner end 19 riveted to the limb 7. The remaining U-shaped unit or section, the one which is horizontally disposed, is denoted by the numeral 20. This comprises a cross limb 21 which is riveted centrally in place as at 22 and which has outstanding end portions 23 terminating in out-turned U-bends 24 which may be regarded as drag or brake shoes 25.

In order to appreciate the significance of the various elements which go to make up the overall frame or rack, it is desirable to point out the essential characteristics thereof. That is to say, the limb 15 of the adjustable L-bracket 11 overhangs the mouth portions of the bags, that is when the bags are correctly stacked in the rack as shown for example in Figures 1 and 2. What is more, the detent 16 on the outer end progressively and successively is hooked down over the intermediate areas of the inner or rear panel C of the bag. This permits the finger-notch or cut-out D in the front panel or wall E to be free of connection with said detent. It also provides an arrangement in which the human finger may be readily hooked and inserted into the bag by way of the finger notch D so that the outward pulling step may be initiated. Due to the fact that the prong 18 presses against the intermediate portions of the bags, it exerts a thrust action thereagainst and bends or bows the bags. As the bags on opposite sides of the prod or prong are temporarily anchored in the frame structure, they are thus placed under tension and the desired follow-up and follow-through results are attained. It is thought, too, that the prong 18 serves as a sort of a fulcrum to assist in removal of the bags in step-by-step fashion. Assuming that a bag has been withdrawn as shown to the right in Figure 2, that is, the upper portion has been grasped and pulled out, it is obvious that the drag action of the detent 16 against the inner wall causes the mouth of the bag to be partly opened. Then, as the bag is gradually yanked downwardly and then outwardly, the hook-like bends 24 snap into the infolds or folded portions F as shown in Figure 4, thus producing a momentary drag or brake action and partly spreading and expanding the fold. So, first the mouth of the bag is opened, then the folds are spread and partly opened. By continuing this one-handed action and pulling the bag out partly opened and swooping it down and through the air, it is inflated in an obvious manner, and then ready for filling.

A careful consideration of the foregoing description in conjunction with the invention as illustrated in the drawings will enable the reader to obtain a clear understanding and impression of the alleged features of merit and novelty suf-

ficient to clarify the construction of the invention as hereinafter claimed.

Minor changes in shape, size, materials and rearrangement of parts may be resorted to in actual practice so long as no departure is made from the invention as claimed.

What is claimed is:

1. A bag holding rack comprising a main U-shaped vertically disposed unit, the upper limb thereof terminating in a depending detent, the lower limb thereof being downwardly and outwardly inclined and terminating in an upstanding keeper-hook, an outstanding prong on the intermediate portion of said unit, a second unit fastened at right angles to the intermediate portion of the first named unit and having outstanding end portions perpendicular to said second unit terminating in U-shaped bends, the bight portions of the latter being directed inwardly toward each other.

2. A paper bag holding and dispensing rack of the class described comprising a cruciform frame structure embodying a vertically disposed relatively long U-shaped unit and a complementary 25 relatively short horizontally disposed U-shaped unit, said units having their central portions disposed in crossed relation and securely riveted together, said long unit being longitudinally extensible and retractable so that it may be adjusted to accommodate bags of varying lengths and embodying means for releasably engaging the upper and lower end portions of bags, the arms of the short U-shaped unit being in a plane perpendicular to said central portion and terminating in U-bends forming drag shoes, the bight portions of said U-bends being directed inwardly toward each other and being engageable with longitudinal edge portions of the bags, and rigid thrust means mounted on the long unit in a 30 plane above said U-bends and adapted to contact and bend portions of said bags.

3. A bag holding rack comprising a main U-shaped vertically disposed unit, the upper limb thereof terminating in a depending detent, the lower limb thereof being downwardly and outwardly inclined and terminating in an upstanding keeper-hook, a single rigid outstanding prong on the intermediate portion of said unit, said prong being in vertical alignment with said upper and lower limbs, a second unit fastened at right angles to the intermediate portion of the first-named unit and having outstanding end portions terminating in U-shaped bends, the outer end of said prong terminating inwardly of said U-shaped bends and the bight portions of the latter being directed inwardly toward each other.
